(57) **CLAIM**

The ornamental design for a light fixture, as shown and described.

DESCRIPTION

FIG. 1 is a front perspective view of a light fixture showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrating portions of the light fixture form no part of the claimed design. The dot-dash broken lines define the bounds of the claimed design and form no part thereof. The oblique shade lines show a translucent or transparent material.

1 Claim, 6 Drawing Sheets
